UNITED STATES PATENT OFFICE.

JOHN HENRY BAUSCHARD, OF ERIE, PENNSYLVANIA.

WALL-FORM TIE.

Application filed July 2, 1923. Serial No. 649,131.

My invention relates to improvements in forms used in erecting concrete walls, etc., and it consists of the constructions, combinations and arrangements herein described and 5 claimed.

An object of the invention is to provide a device to be used in the erection of wooden forms for concrete wall building which will efficiently meet all the requirements of a tie, 10 spreader and gauge for the thickness of the finished wall.

Another object of the invention is to provide a tie of the nature described which will also supply a rigid anchorage for reinforcing rods, frames, conduits, ducts, or any 15 other elements which are required to be fixed in position in the wall between the form board while casting.

A further object of the invention is to 20 provide a sheet metal wall form tie which is so bent that notches may be provided for the reception of the form board, these notches being uniformly spaced apart so that the thickness of the finished wall may be 25 accurately gauged by the mere use of the tie alone.

A further object of the invention is to provide a tie of the character described which is intended to be embodied in the wall, certain 30 projecting portions later being useable as bonds to which a brick veneer may be fastened.

A further object of the invention resides in the herein disclosed method whereby a 35 wall form is erected by alternately superimposing form boards and ties upon each other, the nature of the ties being such as to fix the wall space between boards, the ends of the ties projecting beyond the boards being 40 secured to adjacent uprights so as to hold the longitudinal board edges in close contact.

Other objects and advantages will appear in the following specification, reference being had to the accompanying drawing, in 45 which:

Fig. 1 is a perspective view of one of the improved form ties,

Fig. 2 is an elevation of a portion of a 50 wall form showing how the ties may be distributed to hold the form board,

Fig. 3 is a detail vertical section taken on the line 3—3 of Fig. 2,

Fig. 4 is a detail horizontal section taken 55 on the line 4—4 of Fig. 2, the upright timbers being omitted,

Fig. 5 is a detail vertical section on the line 5—5 of Fig. 2, and

Fig. 6 is a horizontal section of a portion of a wall form illustrating the method of 60 using the form ties at the corners of walls.

The improved form tie is composed of a piece of sheet steel or galvanized sheet metal in any suitable standard gauge, stamped out to form a center web 1 (Fig. 1) a down-turned flange 2 and an upturned flange 3. In cross section the form tie is of a reversed Z shape.

Stamped out of the flanges 2 and 3 are notches 4, 5 and 6, 7 respectively. The pairs 70 of notches 4, 6 and 5, 7 coincide so that the flange 2 may properly be seated upon one course of form board and that the flange 3 may properly receive the next course of form board to be imposed on the course 75 preceding.

It is desired to make special mention of those portions of both the web and upstanding flange that extend beyond the notches described. These portions are distinguished 80 from the main parts of the tie by referring to the web extensions 8 and flange extensions 9. The former are provided with single holes 10 which are disposed close to the adjacent pairs of notches. These holes 85 are for the purpose of permitting nails to be driven into the form board immediately below, in a slanting manner as suggested in Fig. 5. The latter extensions 9 each have a pair of holes 11 for the purpose of nailing 90 to the upright timbers 12 of the form boards 13. The upright flange 3 has a series of holes 14 to which reinforcing rods, frames, etc., may be wired during the course of 95 setting up the wall form.

The general use of the form ties consists of placing them transversely of the wall form as shown both in Figs. 2 and 6. However, there is an additional use to which the ties may be put. Consider the third course 100 of boards in Fig. 2, counting up from the bottom. Here is a pair of boards 15, the ends of which abut in a space between upright timbers. In order to keep the ends of the abutting boards from buckling in any manner and possibly bending out under the pressure of concrete, use is made of a pair of the ties 1, one tie beneath and one on top of the boards in question.

By considering Fig. 5, the reader will see 110 that the down and up turned flanges 2 and 3 respectively so engage the sides of adja-

cent boards, especially the sides of the abutting boards 15, in such a manner as to preclude all possibility of bulging.

The operation is as follows: Let the reader 5 imagine a form for a concrete wall to be under construction. As soon as the bottom course of boards is laid, a plurality of ties 1 are extended across the intermediate space, the notches 4 and 5 in the downturned flanges 10 2 being fitted over the upper edges of said boards. It is advisable to place one of the ties adjacent to each of the upright timbers 12 and it is also advisable to insert ties halfway between the upright pieces. This arrangement 15 is generally used in the lower course only, and here for the obvious reason that it is desirable to start the form with a firm foundation.

The boards of the second course are now 20 stood edgewise on the boards of the first course, the former being inserted in the notches 6 and 7 of the upstanding flange 3. Nails are driven through the holes 11 into adjacent upstanding timbers 12, but these 25 nails need not be driven all the way in and are preferably left projecting so as to permit easy withdrawal.

The foregoing steps are those of a novel 30 method of erecting wall forms, the important features of the method being brought out in the claims.

As succeeding courses of boards are applied, such distribution of ties 1 is made as 35 may seem to the builder to carry with it the requisite amount of bracing to insure a stable structure. At places where form boards abut in a space between uprights, use is made of a pair of the ties, one of which is placed above and below respectively of the abutting 40 ends. The outwardly turned flanges engage the adjacent form board of the courses below and above the abutting boards while the inwardly turned flanges engage the abutting boards on the outside. This arrangement 45 keeps the abutting boards from buckling under the weight of the concrete on the inside.

Whenever it is necessary to incorporate 50 reinforcing rods or to suspend conduits in the wall space between the boards, use is made of the holes 14 for inserting the necessary supporting wire. When the entire form is completed, the concrete is poured in. Those 55 portions of the tie inside of the pairs of notches are embedded in the walls and remain as a part thereof. The various nails are withdrawn and the form boards and timbers are removed, leaving the web and flange extensions 8 and 9.

60 These extensions become useful when other structure is to be built against the concrete wall. This is especially true should it be desired to build a brick veneer wall against the concrete wall. The web and flange extensions 65 may be hammered down against the

concrete wall so as to flatten the angles and when the extension is again bent out, it becomes a bond to the brick work if it occurs on line with a mortar joint.

If the concrete wall is to be left plain, the 70 projecting extensions of the form ties can be removed by bending them up and down two or three times when the ends will break off flush with the wall. In the case of a cellar wall where the earth is to fill in on one side, the projecting extensions may be permitted to remain without further attention. The shape of the tie further permits of close nesting when packing them for shipment. There are a number of features of advantage to be 75 found in the wall tie.

It will be noticeable to the reader that but a small amount of nails is required by making use of this tie, only a comparatively few 80 being required to hold the ties to the various uprights and form boards. It is further to be noted that the boards and uprights are not mutilated by the driving in of numerous nails. The use of but few nails permits the ready separation of the forms after the wall 85 has properly set, and upon removing the various boards, they may be immediately used again in building another form, without having to extract great numbers of nails and causing a consequent damage to the 90 lumber.

According to the old practice of building 95 wall forms, it has been found desirable to use boards of a uniform width so that the board joints on both sides of a wall would 100 come at approximately the same level. This was necessary in order that the various tie wires could be inserted between the joints and around the uprights for tightening. The same requirement as to uniform width 105 of board is also necessary with the use of the arrangement herein disclosed. It is very desirable that the form ties 1 are to lie as near level as possible, and this is readily accomplished by using boards of uniform 110 width, as stated.

According to present methods, it is customary, and indeed necessary, to have the end joints of the boards join at the uprights so 115 that the abutting ends of the boards might be nailed thereto. In order to make the boards come out right, it is often necessary to cut off pieces so that the boards may end at uprights. This is especially true when a board is not quite long enough to reach the next upright. This cutting off of ends occasions a waste of lumber. According to the invention, such waste is unnecessary, inasmuch as abutting ends of boards may be 120 joined in spaces between uprights, as clearly shown in Fig. 2.

While the construction and arrangement 125 of the improved form tie as herein described and claimed, is that of a generally preferred form, obviously modifications and changes

may be made without departing from the spirit of the invention or the scope of the claims.

I claim:

- 5 1. A wall form tie composed of a strip of metal stamped to provide a center web, a flange turned down at right angles along one side and being notched in from the edge to receive the upper edges of form boards in one course, and a flange turned up at right angles along the other side and being notched in from the edge to receive the lower edges of form boards in a superimposed course, said upturned flange between the notches 10 having holes to receive supporting wires, the web and upturned flange beyond said notches having holes to receive nails.
- 15 2. A wall form tie comprising a single rectangular strip of metal which is bent longitudinally at two places to provide a pair of parallel flanges extending in opposite di- 20
- 25 3. A wall form tie comprising a web, parallel downturned and upturned flanges on the longitudinal edges of the web each being notched in alignment to receive the superimposed courses of form boards, each end of the upturned flange beyond the notches 30 having holes permitting nailing down to upright timbers and producing downward pressure upon said boards to make a close joint, said web also having holes beyond said notches permitting nailing the tie to a form board. 35

JOHN HENRY BAUSCHARD.
